(57) CLAIM

The ornamental design for a swimsuit, as shown and described.

DESCRIPTION

FIG. 1 is a front elevational view of a swimsuit showing our new design; and,

FIG. 2 is a left side view corresponding to FIG. 1, with the right side view being a mirror image of FIG. 2.

The broken lines shown in the drawings depict environment that form no part of the claim.

1 Claim, 2 Drawing Sheets
